CARBURETOR FOR INTERNAL COMBUSTION ENGINES

Jesse Wheeler, Long Beach, Calif., assignor of one-half to Lang Transportation Company, Vernon, Calif., a copartnership consisting of Mike Lang, Gene Lang, and Howard M. Lang

Application October 19, 1929. Serial No. 400,874

44 Claims. (Cl. 123—138)

- My invention relates to carbureting devices, for internal combustion engines, and particularly to such mechanisms for effecting a feeding of the combustible gases under pressure.
- 5 One of my objects is to so regulate the fuel feed that delivery of a combustible mixture is made to the intake manifold of the motor at sufficient velocity and pressure to just overcome the vacuum created on the intake stroke of the 10 pistons. In other words, the delivery into the cylinders, on the intake strokes of the pistons, is positive, at substantially atmospheric pressure, and is effected by the mechanism I employ, instead of by suction of the motor.
- 15 Another object is to vary in proportion the quantity of liquid fuel feed in direct ratio to the speed of the motor, thereby obtaining maximum efficiency and combustion, with a minimum of fuel consumption.
- 20 While I am aware that heretofore pump mechanisms have been employed, for delivering liquid fuel to the intake manifold under pressure, the great difficulty encountered has been in timing, regulating and adjusting the pumps, and their 25 driving means—as to velocity and capacity—with such precision that at all times the proper amount of combustible mixture will be delivered without flooding the carburetor. It has been with a view to overcoming this difficulty that I 30 have conceived and perfected the principles embodied in the herein disclosed mechanism.
- In the means I employ I provide a pump, in 35 connection with a carburetor or mixing chamber, geared in timed relation with the main shaft of the motor, to supply the necessary pressure feed of the liquid fuel to the mixing chamber; this being designed, with respect to its size, capacity and velocity, as near as may be, in accordance with the size, speed and fuel requirements of the 40 motor; a rotary valve, which is also geared with the main motor shaft, to effect delivery of liquid fuel to the mixing chamber only on the suction stroke of the piston; and an intermediately disposed, automatic, by-pass member, containing a 45 plurality of fluid pressure actuated by-pass valves, and including means for variably adjusting the pressure resistance of these valves, to be opened by the pressure of the fuel feed, in direct ratio to the extent of opening of the throttle valve and the 50 speed of the motor.
- As I will more fully hereinafter point out, my mechanism automatically supplies the proper amount of liquid fuel to the mixing chamber, proportionately to the speed of the motor, any ex- 55 cess delivered by the pump being automatically by-passed back to the fuel reservoir.
- In addition to the above features I also employ a mixing chamber, including a "hot spot", to effect complete vaporization of the liquid fuel, and also a plurality of positively driven propellers, to insure a complete combustible mixture and proper delivery of the mixture to the intake manifold.
- One clear distinction between my improved device and prior, similar devices, wherein pump mechanisms have been employed to effect a forced fuel feed, is that, by the means I employ, I am enabled to deliver a combustible mixture to the motor cylinders, on the intake stroke, at at least atmospheric pressure, without depending upon the vacuum created by the pistons on their intake strokes for drawing the mixture into the cylinders, and to do so without flooding the mixing chamber and without running the risk of incomplete vaporization of the liquid fuel due to such flooding. In the prior, similar devices, where pumps have been employed, due to the fact that these cannot be accurately regulated and adjusted to nicely supply the needs of the motor at different speeds, an excess of fuel is delivered to the mixing chamber, causing flooding, which also results in forcing the liquid fuel into the cylinders before complete vaporization has been accomplished. This not only results in waste of fuel, but also in inefficient operation of the motor with a consequent loss of power. With my arrangement the pump may, and probably does, normally deliver an excess of fuel over that required for operation of the motor at a given speed, yet, with my automatic feed regulating device, only a given quantity of liquid fuel will reach the mixing chamber, the excess being by-passed back to the fuel reservoir.
- In the following specification I will more particularly point out the merits and advantages of my improvement, together with a detailed description of the structure and operation of my preferred embodiment, this embodiment being illustrated in the accompanying drawings and referred to in the specification. In the drawings—
- Fig. 1 is a side elevation of a typical internal combustion engine, showing the manner in which my improved device is applied thereto;
- Fig. 2 is a top plan view of my arrangement, taken as indicated by the line 2—2 of Fig. 1;

Fig. 18 shows diagrammatic layouts of several 40 different positions of the by-pass valve adjusting rod.

Referring first to Fig. 1, the numeral 20 designates generally a typical four-cylinder, internal combustion engine, and 21 its intake manifold, with which my carbureting mechanism is connected. In Figs. 1 and 2 I have illustrated in side 45 elevation and plan, respectively, my complete assembly as it is applied to a motor. The major elements of my mechanism comprise a pump A, the by-pass B, rotary valve C and carburetor D, operatively connected and combined to produce 50 the results herein set forth.

Taking the above elements and their operative connecting media, in the order of arrangement, a liquid fuel feed pipe 22 leads from a suitable 55 source of supply, such as a fuel tank or reservoir, and discharges into a small auxiliary reservoir or chamber 23. The auxiliary reservoir is adapted to contain only a small quantity of liquid fuel and is merely for the purpose of retaining a sufficient supply of fuel at all times to start the 60 motor. The fuel feed from the pipe 22 is into the top of the auxiliary reservoir 23 and the discharge therefrom is by gravity, through a pipe 24, which connects with the feed side of the pump A. A pressure feed pipe 25 connects the discharge side of the pump A with one end of the main feed passage 26 passing through the by-pass B (Figs. 7 and 8). A pressure feed pipe 27 connects the other end of the main feed passage 26 with the inlet side of the rotary valve C and a feed pipe 28 connects the discharge side of the 65 rotary valve C with the carburetor D, through the needle valve 29. A return flow pipe 30 leads from the by-pass B back to the tank or reservoir from which feed pipe 22 leads, and connected into this 70 75 is a similar return flow pipe 31, leading from a

return flow passage of the rotary valve C. A return flow pipe 32 likewise connects with the return flow pipe 30 and leads from a drainage cup 33 located at the bottom of the mixing chamber D.

The pump A and rotary valve C may be operated from either the generator or half-time shaft of the motor, properly geared to obtain the desired results. In the present case I have shown these members operated from the generator shaft 34, through the medium of an extension shaft 35, coupled with the shaft 34 at 35a.

The pump A may be any one of the usual and well-known types of circulating pumps, of either gear or oscillating construction. It is operatively connected with shaft 35 through the medium of a shaft 36, revolubly journaled in a bearing sleeve 37, and spur gears 38 and 39 (Fig. 17). Inasmuch as the details of construction and operation of circulating pumps of this character are so well-known to those skilled in the art, it is not thought necessary to go further into these matters here, as the details of the pump structure, as such, form no part of my invention.

The rotary valve C is shown in detail in Figs. 12, 13, 14, 15 and 16. This consists of a rotor 40, revolubly mounted within a fluid tight fitting recess 41 in a casing 42. The front end 43 is in the form of a removable cover plate, to admit of easy assembling and access to the rotor for replacement or repairs. The rotor 40 is fixed upon an operating shaft 44, the latter being revolubly journaled in bearing bores 45 and 46 in the cover plate 43 and the casing 42, respectively. A spur gear 47 is fixed upon shaft 44 and meshes with a smaller spur gear 48 fixed upon shaft 35 (Fig. 11). Gears 47 and 48 are enclosed within a casing 49 interposed between and connected with the casing 42 and casing 50 of the pump A (see Fig. 2).

The rotor 40 has an annular channel or recess 51 in one face (Fig. 14) which is adapted to register with an inlet port 52, in casing 42, into which the feed pipe 27 is connected, so that at all times there is fuel under pressure within this channel. A pair of diametrically opposed arcuate apertures 53 and 54, substantially 90° in length and concentric to the axis of the rotor 40, extend through the rotor, from channel 51, and are adapted to intermittently register with an outlet port 55 in cover 43, into which the feed pipe 28 is connected, as shown in Figs. 12 and 13. Extending into the rotor 40 is a pair of diametrically opposed, peripheral recesses 56 and 57, also substantially 90° in length, which are adapted to intermittently register with a port 58 into which the return flow pipe 31 is connected.

Apertures 59 and 60 connect recesses 56 and 57 with the annular channel 51, so that at all times there is fluid under pressure within the recesses 56 and 57.

The rotor 40, driven through gears 47 and 48, is rotated at the same speed as the main motor shaft. As in a four-cylinder motor there are two intake strokes and two explosions upon each revolution of the main motor shaft, each of the apertures 53 and 54 will successively register with the port 55, during each revolution, and recesses 56 and 57 will likewise successively register with the port 58 during each revolution. The apertures 53 and 54 are each positioned to register with port 55, in timed relation with the intake strokes of the pistons, and intermediate these strokes the recesses 56 and 57 successively register with ports 58, so that at all times a substan-

150

tially even pump pressure may be maintained within the annular recess 51, apertures 53 and 54 and recesses 56 and 57 during operation of the motor. In this manner excessive pressure is not built up within the rotary valve, resulting in an excessive supply of liquid fuel being discharged into the carburetor D through the feed pipe 28.

The details of the by-pass B are illustrated in Figs. 7, 8, 9 and 10. This consists of a block 61 through which the main fuel feed passage 26 extends, and into one end of which the return feed pipe 30 is secured, to connect with a drainage passage 62 which extends substantially parallel with the passage 26. The plurality of bores 63a, 63b and 63c extend upwardly from the bore 26 and connect with a bore 63 which likewise extends substantially parallel with the bore 26. Bores 63a, 63b and 63c are reduced at their ends adjacent the bore 26 to form valve seats 64 and restricted inlet passages 65. Bores 66, situated above the seats 64 (Fig. 9), connect bores 63a, 63b and 63c with the bore 62. An adjusting rod 67 is mounted longitudinally slideable in bore 63, the latter being closed at one end by a plug 68 and provided at its opposite end with a packing gland 69, to insure a fluid tight seal during longitudinal movement of the rod 67. Each of the inlet apertures or ports 65 is normally closed by a ball valve 70, these being held normally seated by expandible helical springs 71 which are held under compression by similar balls 72 engaging the rod 67. The under face of the rod 67 is provided with notches 73a, 73b and 73c, having relatively elongated inclined faces 75a, 75b and 75c, respectively, adapted to be engaged by the balls 72 during longitudinal movement of the rod 67.

A screw 78 extending into a slot 79 (Fig. 7) serves to limit longitudinal movement of the rod 67. An aperture 80 may be provided between bores 63 and 62 to permit drainage of any leakage from the former into the latter. Screws 72a, having pointed inner ends, may be provided for increasing the normal compressive strength of springs 71.

The rod 67 is operatively connected with the throttle valve lever 81 (Fig. 1) through the medium of a connecting rod 82 and a flexible joint 83, so that when the throttle valve is closed the rod 67 will be in the position illustrated in Fig. 7, and when the throttle valve is open it will be in the position illustrated in Fig. 8.

In Fig. 18 I have illustrated diagrammatically several positions of the rod 67 during operation. The diagram designated "E" shows the relative positions of the notches 73a, 73b and 73c, and balls 72 in bores 63a, 63b and 63c, when the rod 67 is in its position corresponding to the closed position of the throttle valve 99. Diagram F illustrates the relative positions of these parts when the throttle valve is partly open, and diagram G shows their relative positions when the throttle valve is almost entirely open. In the diagram E, normally, the balls 72 in bores 63a and 63b rest within their respective notches 73a and 73b, while at this time the spring 71 in bore 63c is held, by the ball 72 engaging the bottom face of the rod 67, to its maximum compression. The spring 71 in bore 63a is such that when the ball 72 is resting within the notch 73a it will resist fluid pressure in the passage 26 up to from one and one-half to three pounds per square inch, and the ball 70 will be raised off its seat by a fluid pressure above that amount. When the spring 71 in bore 63a is compressed to its maximum, the coils will be substantially together

and it will resist a fluid pressure up to twenty pounds or more per square inch. The spring 71 in bore 63b is heavier and has fewer convolutions than the spring in bore 63a so that normally, when its ball 72 is resting within the notch 73b it will resist a pressure in the passage 26 up to five pounds per square inch and when compressed to its maximum, as shown in the diagram G (Fig. 18) it will resist a fluid pressure in the passage 26 up to about twenty pounds per square inch. When the ball 72 in bore 63c is in engagement with the bottom face of the rod 67, as shown in the diagram E, Fig. 18, its spring 71 is such that it will resist a fluid pressure in the passage 26 up to about twenty pounds per square inch, and when its ball 72 is seated within its notch 73c, as shown in the diagram F, Fig. 18, it will resist a fluid pressure up to about ten pounds per square inch.

This by-pass arrangement is such that at starting or idling speed the fluid pressure required in the feed line is from one and one-half to three pounds per square inch, and when the pressure in passage 26 raises above that amount it will be by-passed through the bores 65, 63a and 66, into the bore 62, and return to the storage tank through the return pipe 30. In case, at low speed, the pressure in passage 26 should rise up to and exceed five pounds per square inch, this excessive pressure would then also raise the ball 64, in bore 63b, against the action of its spring 71, also permitting this excess of fluid to return to the storage tank through the bore 62 and pipe 30. This provides a safety by-pass and compensates for any slight inaccuracies in the strength of the springs in these two bores. As the throttle valve is opened the rod 67 is moved to the left, in Figs. 7, 8 and 18, compressing the springs 71 in bores 63a and 63b, checking against the increase in fluid pressure required to supply the motor needs. This movement is shown in the diagram F, Fig. 18, and also shows that the ball 72 in bore 63c has been forced upwardly into its notch 73c, thereby reducing the compression upon its complementary spring 71 to about ten pounds per square inch. Upon further opening of the throttle valve, necessitating further increased pressure to supply the motor needs, springs 71 in bores 63a and 63b will be further compressed, thus requiring an increased pressure in passage 26 to effect by-passing of any fluid into the bore 62 and return pipe 30. During this time any increase in pressure up to ten pounds per square inch, not required for motor operation, will be by-passed through the bores 63a and 63b. On further movement of the rod 67 by-passing, at any pressure, will be prevented through the bore 63a and the springs 71 in bores 63b and 63c will be correspondingly compressed so that it will require a correspondingly greater fluid pressure in passage 26 to by-pass any fluid therethrough. When compressed to their maximum, as illustrated in Fig. 8, springs 71 in bores 63b and 63c will resist fluid pressure in passage 26 up to about twenty to twenty-five pounds per square inch, which is about that required to supply fuel to the motor operating at its maximum speed. Should the pressure rise above this in passage 26, it will be by-passed, as before stated, through bores 63b and 63c and return line 30 to the fuel reservoir.

The carburetor D consists of a casing 85 forming the mixing chamber 86; the casing 85 being constricted at its upper end to form a tubular neck 87, this being provided at its upper end

with a peripheral flange 88 by means of which it may be bolted to a complementary flange 89, of the intake manifold 21. The casing 85 is preferably cylindrical and is closed at its bottom by means of a plate 91, removably secured thereto by screws 92, or other suitable means. A housing 93, preferably formed integral with plate 91, depends beneath the casing 85, this being more clearly shown in Figs. 4 and 5. A shaft 94, revolvably journaled at its lower end in a suitable ball bearing 95, in the bottom of housing 93, extends upwardly through a guide bearing 96, in plate 91, concentrically with the casing 85 and neck 87 (Figs. 3, 4 and 5). A propeller 97 is secured upon shaft 94, with its horizontal center in a plane with the mouth or lower end of the neck 87, as shown in Fig. 3, and a second propeller 98 is secured to the upper end of shaft 94 at a point as near the top of neck 87 as possible to permit proper action of the throttle valve 99, the latter being positioned at the extreme upper end of neck 87 and operable through the medium of the lever 81 (Fig. 1). The pitch of the blades of propeller 98 is higher than the pitch of the blades of propeller 97, in the present case the blades of propeller 97 being shown at about 27°, while the pitch of the blades of propeller 98 are about 5° higher, or 32°. By this arrangement fluid pressure is not only created and a fluid flow effected through the neck 87, into the intake manifold, but this pressure is maintained within the intake manifold 21 substantially constant.

Shaft 94 is driven through the medium of a worm gear 100, keyed upon shaft 35, and a worm wheel 101 keyed upon shaft 94, within the housing 93; shaft 35 being revolvably journaled in suitable bearings 102 and 103 in opposite walls of the housing 93, as shown in Fig. 5.

40 An air intake aperture 104 is provided in one side of the casing 85, being equipped with an intake tube 105 in which there is a valve 106 for purposes of adjustment under certain conditions. A deflector plate 107 is placed over the 45 intake aperture 104 to direct the incoming air, as indicated by the arrows in Fig. 4, around and spirally within the casing 85. This deflector plate 107 directs the incoming air around and over a "hot spot" 108 and the upper or discharge end 109 of the needle valve 29, situated 50 directly therebeneath, both the "hot spot" 108 and the needle valve discharge end 109 being substantially diametrically opposite the air inlet 104.

55 The "hot spot" 108 may be of any of the usual constructions, consisting of a metallic cap 111, secured to a base plate 112, and providing a space therein for the reception of the usual current resistant element (not shown) for generating heat. Electrical conductors 113 and 114, one of which leads to a suitable source of electrical energy, such as a battery (not shown), and the other grounded upon the casing 85, as shown in Fig. 1, connect with the current resistant element. These conductors lead through a tubular stem 115, by means of which the "hot spot" is mounted in the casing wall 85, as shown in Fig. 3, suitable non-conductive material 116 being provided, surrounding the tube 115, to 70 insulate it from the casing 85.

The needle valve 110 may be of any of the usual constructions, consisting of a tubular member 117 extending upwardly through the housing 93 and screw-threadedly engaging a securing nut 118, in plate 91, as shown in Fig. 3.

The feed pipe 28 is removably secured to a T fitting 119, on the lower end of the tube 117, by means of a suitable union 120. The usual adjustment for the needle 121 is provided in a screw-threaded connection between its lower end 122 and a removable plug 123 in fitting 119; a knurled head 124 being provided on the bottom end of the needle for manual adjustment.

The upper end 109 of the needle valve is restricted, as at 125, to produce a spraying effect, 85 and the bottom face 126, of the "hot spot" 108, is inclined at an angle to deflect the sprayed and vaporized gases outwardly into the casing 85, to be fully comingled with the incoming air, and to be drawn upwardly and directed through 90 the neck 87 by propellers 97 and 98.

The areas of the air inlet aperture 104 and the discharge end 127, of the neck 87, are both 95 the same as the area of the inlet passage into the engine manifold at 21.

To take care of any excess of fuel that may possibly gather in the bottom of the casing 85, and to avoid flooding of the carburetor, the drainage chamber 33 is provided, depending from the plate 91 and removably secured thereto as 100 by means of screws 128. A drain tube 129 is secured in the bottom plate 91 to drain into the chamber 130 of cup 33, this being provided at its lower end with a gravity seated, non-return flop valve 131. As liquid fuel gathers in the chamber 130 it will drain back to the storage tank 105 through the return flow pipe 32.

In the operation of my device, assuming the motor to be at idling speed, the throttle valve 99 is partly opened as shown in Fig. 3 and the rod 110 110 67 is in the position diagrammatically illustrated at E in Fig. 18. In this position the spring 71 in bore 63c is compressed to its maximum, while the springs 71 in bores 63a and 63b are under their minimum compression. The rotor 40, of the rotary valve C, revolving at the same speed as the main shaft of the motor, delivers liquid fuel, under pressure, to the carburetor D in timed relation with the intake stroke of the pistons. It is, of course, to be understood that registration of the 120 apertures 53 and 54, of the rotor 40, will be timed a little in advance of the actual opening of the intake valves, in order to deliver the combustible mixture into the intake manifold at the proper time. When apertures 53 or 54 are not in registration with port 55 to deliver liquid fuel to the carburetor through feed pipe 28, one of the recesses 56 or 57 will be in registration with aperture 58 and delivering liquid fuel under pressure 125 through return pipe 31 to the fuel tank. In this manner a substantially even pressure is maintained within the rotary valve, and there is no danger of building up a back pressure which will result in intermittently discharging an excess amount of liquid fuel into the carburetor. 130 135

In case the pump A delivers liquid fuel at a pressure in excess of that required for idling speed (assuming the motor to be still operating at idling speed), that is, more than from about one and a half to three pounds per square inch, this 140 excess of pressure will raise the ball 70 in bore 63a off its seat, permitting the excess fluid to be bypassed through passage 62 and return pipe 30 to the fuel reservoir. If the throttle valve is opened farther, resulting in increased speed of the 145 motor and necessarily increased speed of the pump A and the delivery of fuel under higher pressure, the operation will be the same unless the pump delivers liquid fuel at a pressure in excess of five pounds per square inch, and more 150

than enough to be by-passed through the bore 63a, the increase over five pounds per square inch will raise the valve 70 off its seat in bore 63b, so that this excess will be by-passed through both of the

5 bores 63a and 63b. If the throttle valve is further opened and the rod 67 moved toward the position shown in diagram F, Fig. 18, and the fuel requirements of the motor be greater, the springs 71 in bores 63a and 63b will be further compressed, requiring a higher pressure in bore 26 to raise the balls 70 off their seats, consequently fluid will be delivered to the carburetor, through the rotary valve feed, at a higher pressure. When the rod 67 is in the position shown in diagram F, 10 Fig. 18, it will require fluid pressure of between five and ten pounds per square inch to by-pass through the bores 63a and 63b, and as the ball 72 in bore 63c within its notch 73b, in rod 67, fluid will be by-passed through all three of the bores 15 in case the fluid pressure raises above ten pounds per square inch. Further movement of the rod 67 to the position shown in diagram G, Fig. 18, will result in the spring 71 in bore 63a being fully compressed, closing that passage against any pressure, the excessive pressure thereafter being by-passed through bores 63b and 63c. Under these 20 circumstances the spring 71 in bore 63b will resist fluid pressure in passage 26 up to about twenty pounds per square inch, while the spring in bore 63c will resist fluid pressure up to about fifteen pounds per square inch. Full movement of the rod 67, to fully compress all of the springs, as 25 shown in Fig. 8, will resist fluid pressure in passage 26 up to about twenty pounds per square 30 inch.

As the liquid fuel is intermittently discharged into the carburetor D, through the needle valve 29, it is sprayed upon the bottom face 126 of the "hot spot" 108, thus not only diffusing it, but 35 also vaporizing it to the fullest extent. The incoming air, through the inlet 104, being spirally directed around the mixing chamber 86, will fully mix with the vaporized liquid fuel and thence be drawn and directed upwardly through the neck 40 87 by propellers 97 and 98. Propeller 97 being located in a plane at exactly the mouth of the neck 87 not only draws the vaporized gases toward the neck but boosts them up into it, where 45 they are further picked up and boosted by the propeller 98. The pitch of the blades of propellers 97 and 98 are such that a substantially constant fluid pressure is maintained within the manifold 21 during operation of the motor, and while the flow of fluid is intermittent, during 50 operation of the motor, the discharges of liquid fuel into the carburetor are so close together that a substantially even flow of the combustible mixture is maintained in the manifold 21, without discharge of an excessive amount of liquid 55 fuel into the carburetor.

While I have herein shown and described the preferred specific embodiment of my invention, I do not thereby necessarily limit myself to details precisely as shown, but reserve the right to make such changes or modifications in structure as will come within the scope of the claims appended hereto. For instance, in adjusting my mechanism to motors of different sizes and speeds, and different fuel requirements, it is to be understood that the size and speed of rotation of the pump A may be varied, together with its gearing connections; the size and speed of rotation, as well as the number of discharge apertures, of the rotary valve C may be varied; and also the size and capacity, as well as the number of by-pass valves,

of the by-pass B, may be varied to suit particular conditions. Modifications of the needle valve may also be necessary, depending upon the type and speed of motor to be operated.

Having described my invention, I claim:

1. In a device of the character described, the combination of: a liquid fuel reservoir; a carburetor; a fuel feed pipe connecting said reservoir and carburetor; means operatively connected in said feed pipe for feeding fuel to the carburetor under pressure; valve means operatively connected in said feed pipe adapted to intermittently feed fuel to the carburetor; by-pass means operatively connected in said feed pipe, intermediate the pressure feed means and the valve means, adapted to automatically regulate the pressure of the fuel feed to the carburetor; there being a return flow pipe from the valve means to the fuel reservoir and a return flow pipe from the by-pass means to said reservoir.

2. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir.

3. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir; and means operatively connected in said fuel feed pipe, intermediate the pressure feed means and said valve, adapted to regulate the pressure of the fuel feed to the carburetor.

4. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow line to the reservoir; and fluid pressure actuated means operatively connected in said fuel feed pipe, intermediate the pressure feed means and said valve, adapted to automatically regulate the pressure of the fuel feed to the carburetor.

5. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir; by-pass means operatively connected in said fuel feed pipe, intermediate the pressure feed means and the valve, adapted to regulate the pressure of the fuel feed to the carburetor;

and a return flow pipe leading from said by-pass means to the reservoir.

6. In a device of the character described, the combination of a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir; fluid pressure actuated by-pass means operatively connected in said fuel feed pipe, intermediate the pressure feed means and the valve, adapted to automatically regulate the pressure of the fuel feed to the carburetor; and a return flow pipe leading from said by-pass means to the reservoir.

20 7. In a device of the character described, the combination of: a liquid fuel reservoir; a carburetor; a fuel feed pipe connecting said reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from said by-pass means to the reservoir; said by-pass means having a plurality of spring-seated by-pass valves and means to vary the seating force of the valve springs.

35 8. In a device of the character described, the combination of: a liquid fuel reservoir; a carburetor; a fuel feed pipe connecting said reservoir and carburetor; means operatively connected in said fuel feed pipe for feeding fuel to the carburetor under pressure; valve means operatively connected in said feed pipe adapted to intermittently feed fuel to the carburetor; by-pass means operatively connected in said feed pipe, intermediate the pressure feed means and the valve means, adapted to automatically regulate the pressure of the fuel feed to the carburetor; there being a return flow pipe from the valve means to the fuel reservoir and a return flow pipe from the by-pass means to the reservoir; said by-pass means having a plurality of spring-seated by-pass valves and means to vary the seating force of the valve springs.

40 9. In a device of the character described, the combination of: a liquid fuel reservoir; a carburetor; a fuel feed pipe connecting said reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from said by-pass means to the reservoir; said by-pass means having a plurality of spring-seated by-pass valves, normally adapted to be opened at different pressures, and means to vary the seating force of the valve springs.

45 10. In a device of the character described, the combination of: a liquid fuel reservoir; a carburetor; a fuel feed pipe connecting said reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from said by-

50 pass means to the reservoir; said by-pass means having a plurality of by-pass passages connecting said fuel feed pipe and said return flow pipe; valves in said passages; springs normally holding said valves in closed position, said springs each being adapted to yield to different fluid pressures in the fuel feed pipe.

55 11. In a device of the character described, the combination of: a liquid fuel reservoir; a carburetor; a fuel feed pipe connecting said reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from the said by-pass means to the reservoir; said by-pass means having a plurality of by-pass passages connecting said fuel feed pipe and said return flow pipe; valves in said passages; springs normally holding said valves in closed position, said springs each being adapted to yield to different fluid pressures in the fuel feed pipe; and means to vary the seating force of the valve springs.

60 12. In a device of the character described, the combination of: a liquid fuel reservoir; a carburetor; a fuel feed pipe connecting said reservoir and carburetor; means operatively connected in said feed pipe for feeding fuel to the carburetor under pressure; valve means operatively connected in said feed pipe adapted to intermittently feed fuel to the carburetor; by-pass means operatively connected in said feed pipe, intermediate the pressure feed means and the valve means, adapted to automatically regulate the pressure of the fuel feed to the carburetor; there being a return flow pipe from the valve means to the fuel reservoir; a return flow pipe from the by-pass means to said reservoir; said by-pass means having a plurality of by-pass passages connecting said fuel feed pipe and said return flow pipe; valves in said passages; springs normally holding said valves in closed position, said springs each being adapted to yield to different fluid pressures in the fuel feed pipe.

65 13. In a device of the character described, the combination of: a liquid fuel reservoir; a carburetor; a fuel feed pipe connecting said reservoir and carburetor; means operatively connected in said fuel feed pipe for feeding fuel to the carburetor under pressure; valve means operatively connected in said feed pipe adapted to intermittently feed fuel to the carburetor; by-pass means operatively connected in said feed pipe, intermediate the pressure feed means and the valve means, adapted to automatically regulate the pressure of the fuel feed to the carburetor; there being a return flow pipe from the valve means to the fuel reservoir and a return flow pipe from the by-pass means to said reservoir; said by-pass means having a plurality of by-pass passages connecting said feed pipe and said flow pipe; valves in said passages; springs normally holding said valves in closed position, said springs each being adapted to yield to different fluid pressures in the fuel feed pipe; and means to vary the seating force of the valve springs.

70 14. The combination with an internal combustion engine having a throttle valve, of a liquid fuel reservoir; a carburetor; a fuel feed pipe connecting said reservoir and carburetor; means operatively connected in said fuel feed pipe for feeding fuel to the carburetor under pressure; by-pass means operatively connected in said fuel feed pipe, intermediate the pressure feed means and the pressure feed pipe, adapted to regulate the pressure of the fuel feed to the carburetor; and a return flow pipe from said by-

means to vary the seating force of the valve springs.

22. The combination with an internal combustion engine having a throttle valve, of a liquid fuel reservoir; a carburetor; a fuel feed pipe connecting said reservoir and carburetor; means operatively connected in said fuel feed pipe for feeding fuel to the carburetor under pressure; a rotary valve operatively connected in said feed pipe; a return flow pipe connecting said valve and reservoir, said valve being adapted to intermittently pass liquid fuel to the carburetor and into the return flow line to the reservoir; by-pass means operatively connected in said fuel feed pipe, intermediate the pressure feed means and the carburetor, adapted to regulate the pressure of the fuel feed to the carburetor; a return flow pipe from said by-pass means to the reservoir; said by-pass means having a by-pass passage connecting said fuel feed pipe and said return flow pipe; a valve in said passage; a spring holding said valve normally seated; and means to vary the seating force of the valve spring, said last named means being operative in timed relation with the throttle valve.

23. The combination with an internal combustion engine having a throttle valve, of a liquid fuel reservoir; a carburetor; a fuel feed pipe connecting said reservoir and carburetor; means operatively connected in said fuel feed pipe for feeding fuel to the carburetor under pressure; a rotary valve operatively connected in said feed pipe; a return flow pipe connecting said valve and reservoir, said valve being adapted to intermittently pass liquid fuel to the carburetor and into the return flow line to the reservoir; by-pass means operatively connected in said fuel feed pipe, intermediate the pressure feed means and the carburetor, adapted to regulate the pressure of the fuel feed to the carburetor; a return flow pipe from said by-pass means to the reservoir; said by-pass means having a by-pass passage connecting said fuel feed pipe and said return flow pipe; a valve in said passage; a spring holding said valve normally seated; and means to vary the seating force of the valve spring, said last named means being operative to increase the seating force of said valve spring in proportion to the opening movement of the throttle valve and vice versa.

24. The combination with an internal combustion engine having a throttle valve, of a liquid fuel reservoir; a carburetor; a fuel feed pipe connecting said reservoir and carburetor; means operatively connected in said fuel feed pipe for feeding fuel to the carburetor under pressure; a rotary valve operatively connected in said feed pipe; a return flow pipe connecting said valve and reservoir, said valve being adapted to intermittently pass liquid fuel to the carburetor and into the return flow line to the reservoir; by-pass means operatively connected in said fuel feed pipe, intermediate the pressure feed means and the carburetor, adapted to regulate the pressure of the fuel feed to the carburetor; and a return flow pipe from said by-pass means to the reservoir; said by-pass means having a plurality of by-pass passages connecting said fuel feed pipe and said return flow pipe; valves in said passages, springs holding said valves normally seated, said springs each being adapted to yield to different fluid pressures in the feed pipe; and means to vary the seating force of the valve springs, said last named means being operative in timed relation with the throttle valve.

25. The combination with an internal combustion engine having a throttle valve, of a liquid fuel reservoir; a carburetor; a fuel feed pipe connecting said reservoir and carburetor; means operatively connected in said fuel feed pipe for feeding fuel to the carburetor under pressure; a rotary valve operatively connected in said feed pipe; a return flow pipe connecting said valve and reservoir, said valve being adapted to intermittently pass liquid fuel to the carburetor and into the return flow line to the reservoir; by-pass means operatively connected in said fuel feed pipe, intermediate the pressure feed means and the carburetor, adapted to regulate the pressure of the fuel feed to the carburetor; and a return flow pipe from said by-pass means to the reservoir; said by-pass means having a plurality of by-pass passages connecting said fuel feed pipe and said return flow pipe; valves in said passages; springs holding said valves normally seated, said springs each being adapted to yield to different fluid pressures in the feed pipe; and means to vary the seating force of the valve springs, said last named means being operative to increase the seating force of said valve springs in proportion to the opening movement of the throttle valve and vice versa.

26. The combination with an internal combustion engine having a throttle valve, of a carburetor; a liquid fuel reservoir; a fuel feed pipe connecting said carburetor and reservoir; means operatively connected in said fuel feed pipe for feeding fuel to the carburetor under pressure; fluid pressure actuated by-pass means operatively connected in said fuel feed line, intermediate the pressure feed means and the carburetor, adapted to automatically regulate the pressure of the fuel feed to the carburetor; a return flow pipe connecting said by-pass means and the reservoir; and means to variably adjust the by-pass means to be actuated by different fluid pressures in the fuel feed pipe, said last named means being operative in timed relation with the throttle valve.

27. In a device of the character described, the combination of: a carburetor; means for feeding fuel to the carburetor under pressure; and means, intermediate the pressure feed means and the carburetor, for regulating the pressure of the fuel feed to the carburetor, said carburetor comprising a mixing chamber having an air intake aperture therein, a needle valve connected with the fuel feed line and discharging into the mixing chamber, a heating element in said mixing chamber positioned to be impinged by the discharge from the needle valve, and propeller means in said mixing chamber positioned to mix and discharge the combustible mixture from the mixing chamber.

28. In a device of the character described, the combination of: a carburetor; means for feeding fuel to the carburetor under pressure; and means, intermediate the pressure feed means and the carburetor, for regulating the pressure of the fuel feed to the carburetor, said carburetor comprising a mixing chamber having an air intake aperture therein and having a constricted neck portion adapted to connect with the intake manifold of an internal combustion engine, a needle valve connected with the fuel feed pipe and discharging into the mixing chamber, a heating element in said mixing chamber positioned to be impinged by the discharge from the needle valve, and propeller means in said mixing chamber positioned to mix and discharge the combustible mixture from the mixing chamber.

- ble mixture from the mixing chamber, said propeller means comprising a shaft extending into the neck portion, means to rotate the shaft, propeller blades on said shaft at the entrance to the neck portion, propeller blades on said shaft positioned in the neck portion above the first named propeller blades and having a higher pitch than said first named propeller blades, and a throttle valve positioned above said last named propeller blades.
29. In a device of the character described, the combination of: a liquid fuel reservoir; a carburetor; a fuel feed pipe connecting said fuel feed reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from said by-pass means to the reservoir; said carburetor comprising a mixing chamber having an air intake aperture therein, a needle valve connected with the fuel feed line and discharging into the mixing chamber, a heating element in said mixing chamber positioned to be impinged by the discharge from the needle valve, and propeller means in said mixing chamber positioned to mix and discharge the combustible mixture from the mixing chamber.
30. In a device of the character described, the combination of: a liquid fuel reservoir; a carburetor; a fuel feed pipe connecting said fuel feed reservoir and carburetor; means operatively connected in said fuel feed pipe for feeding fuel to the carburetor under pressure; by-pass means operatively connected in said fuel feed pipe, intermediate the pressure feed means and the carburetor, adapted to regulate the pressure of the fuel feed to the carburetor; and a return flow pipe from said by-pass means to the reservoir; said carburetor comprising a mixing chamber having an air intake aperture therein and having a constricted neck portion adapted to connect with the intake manifold of an internal combustion engine, a needle valve connected with the fuel feed pipe and discharging into the mixing chamber, a heating element in said mixing chamber positioned to be impinged by the discharge from the needle valve, and propeller means in said mixing chamber positioned to mix and discharge the combustible mixture from the mixing chamber.
31. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir; said carburetor comprising a mixing chamber having an air intake aperture therein, a needle valve connected with the fuel feed line and discharging into the mixing chamber.
32. In a device of the character described, the combination of: a liquid fuel reservoir; a carburetor; a fuel feed pipe connecting said reservoir and carburetor; means operatively connected in said feed pipe for feeding fuel to the carburetor under pressure; a rotary valve operatively connected in said feed pipe; a return flow pipe connecting said valve and reservoir; said valve being adapted to intermittently pass liquid fuel to the carburetor and into the return flow pipe to the reservoir; said carburetor comprising a mixing chamber having an air intake aperture therein and having a constricted neck portion adapted to connect with the intake manifold of an internal combustion engine, a needle valve connected with the fuel feed pipe and discharging into the mixing chamber, a heating element in said mixing chamber positioned to be impinged by the discharge from the needle valve, and propeller means in said mixing chamber positioned to mix and discharge the combustible mixture from the mixing chamber, said propeller means comprising a shaft extending into the neck portion, means to rotate the shaft, propeller blades on said shaft at the entrance to the neck portion, propeller blades on said shaft positioned in the neck portion above the first named propeller blades and having a higher pitch than said first named propeller blades, and a throttle valve positioned above said last named propeller blades.
33. In a device of the character described, the combination with an internal combustion engine of: a carburetor; means for feeding fuel to the carburetor under pressure; and fluid-pressure-actuated means, intermediate the pressure feed means and the carburetor, for regulating the pressure of the fuel feed to the carburetor, the latter means embodying a by-pass having means adapted to present resistance to the fuel pressure, and means to automatically increase said resistance proportionately with increased speed of the engine.
34. In a device of the character described, the combination of: a carburetor; a throttle valve associated with the carburetor; means for feeding fuel to the carburetor under pressure; and means, intermediate the pressure feed means and the carburetor, for regulating the pressure of the fuel feed to the carburetor, the latter means embodying a by-pass having yielding means adapted to present resistance to the fuel, and means operatively connected with said throttle valve to increase said resistance of the yielding means.
35. In a device of the character described, the combination of: a carburetor; means for feeding fuel to the carburetor under pressure; and means, intermediate the pressure feed means and the carburetor, for regulating the pressure of the fuel feed to the carburetor, the latter means embodying plural by-pass channels having means adapted to normally present progressive stages of resistance to the pressure feed means, and means for increasing the resistance at the individual channels.
36. In a device of the character described, the combination with an internal combustion engine of: a carburetor; means for feeding fuel to the carburetor under pressure; and means, intermediate the pressure feed means and the carburetor, for regulating the pressure of the fuel feed to the carburetor, the latter means embodying plural by-pass channels having means adapted to normally present progressive stages of resistance to the pressure feed means, and means for increasing the resistance at the individual channels.

- state the pressure feed means and the carburetor, for regulating the pressure of the fuel feed to the carburetor, the latter means embodying plural by-pass channels having means adapted to normally present progressive stages of resistance to the pressure feed means, and means for automatically increasing the resistance at the individual channels proportionately with increased speed of the engine.
37. In a device of the character described, the combination of: a carburetor; a throttle valve associated with the carburetor; means for feeding fuel to the carburetor under pressure; and means, intermediate the pressure feed means and the carburetor, for regulating the pressure of the fuel feed to the carburetor, the latter means embodying plural by-pass channels having means adapted to normally present progressive stages of resistance to the pressure feed means, and means operatively connected with said throttle valve for increasing resistance at the individual channels.
38. In a device of the character described, the combination of: a carburetor; means for feeding fuel to the carburetor under pressure; and means, intermediate the pressure feed means and the carburetor, for regulating the pressure of the fuel feed to the carburetor, the latter means embodying a by-pass having a plurality of yielding means each adapted to present a different degree of resistance to the fuel pressure and means to control said plurality of yielding means.
39. In a device of the character described, the combination of: a carburetor; means for feeding fuel to the carburetor under pressure; and means, intermediate the pressure feed means and the carburetor, for regulating the pressure of the fuel feed to the carburetor, the latter means embodying plural by-pass channels and yielding means adapted to normally present progressive stages of resistance to the pressure feed means, and means for increasing the yielding resistance at the individual channels.
40. In a device of the character described, the combination of: a liquid fuel reservoir; a carburetor; a fuel feed pipe connecting said reservoir and carburetor; means operatively connected in said fuel feed pipe for feeding fuel to the carburetor under pressure; means operatively connected in said fuel feed pipe for regulating the pressure of the fuel feed to the carburetor; and a return flow pipe from said regulating means to the fuel reservoir, the last named means embodying a plurality of adjustable yielding valves each adapted to present a different

range of resistance to the passage of fuel to the return flow pipe and means to control the resistance of said plurality of valves.

41. In a device of the character described, the combination with an internal combustion engine of: a liquid fuel reservoir; a carburetor; a fuel feed pipe connecting said reservoir and carburetor; means operatively connected in said fuel feed pipe for feeding fuel to the carburetor under pressure; means operatively connected in said fuel feed pipe for regulating the pressure of the fuel feed to the carburetor; and a return flow pipe from said regulating means to the fuel reservoir; the last named means embodying yielding means adapted to present resistance to the passage of fuel to the return flow pipe and means to automatically increase said resistance proportionately with increased speed of the engine.

42. In a device of the character described, the combination of: a liquid fuel reservoir; a carburetor; a throttle valve associated with said carburetor; a fuel feed pipe connecting said reservoir and carburetor; means operatively connected in said fuel feed pipe for feeding fuel to the carburetor under pressure; means operatively connected in said fuel feed pipe for regulating the pressure of the fuel feed to the carburetor; and a return flow pipe from said regulating means to the fuel reservoir, the last named means embodying yielding means adapted to present resistance to the passage of fuel to the return flow pipe and means to automatically increase said resistance proportionately with increased speed of the engine.

43. In a device of the character described, the combination with a carburetor, of means for feeding fuel to the carburetor under pressure; means adapted to intermittently feed fuel to the carburetor; and means for regulating the pressure of the fuel feed to the carburetor, the last means embodying a by-pass having yielding means adapted to present resistance to the fuel pressure, and automatic means to increase said resistance.

44. The combination with a carburetor of: a throttle valve associated with the carburetor; means for feeding fuel to the carburetor under pressure; means adapted to intermittently feed fuel to the carburetor; and means for regulating the pressure of the fuel feed to the carburetor, the last means embodying a by-pass having valve means adapted to be opened by pressure of the fuel feed, and means operatively connected with said throttle valve to control the resistance of said valve means.
